NEEDLE-CONTROLLING MECHANISM FOR
KNITTING MACHINES

Rudolph Bassist, New York, N. Y.

Application April 28, 1945, Serial No. 590,814

2 Claims. (Cl. 66—98)

1

My present invention relates generally to knitting machines, and has particular reference to an improved needle-controlling mechanism.

While not necessarily restricted in all its phases to any particular type of knitting machine, my invention is primarily intended for and applicable to the kind of knitting machine which employs a needle of the so-called "spring beard" type. A needle of this kind comprises a shank and a turned-back beard, there being a yieldably resilient articulation between the beard and shank whereby the beard is constantly urged into an open yarn-receiving position spaced from the shank. During a predetermined phase of the knitting cycle, viz., when it is desired to entrap the yarn in the crook of the needle and guide it through a previously-completed loop of the knitted fabric, a so-called "presser bar" or equivalent mechanical element is caused to bear upon the beard and press it into contact with the shank, this pressure being maintained until the beard and shank are safely through the previously-knitted loop. Upon subsequent withdrawal of the presser bar or the like, the beard re-assumes its normal open disposition with respect to the shank.

The use of a presser-bar of the general type mentioned, and the operation described, are well-known in the knitting machine art.

It is a general object of my present invention to provide an improved mechanism whereby the need for a presser bar may be dispensed with. This achieves the desirable advantage of simplifying the knitting machine structure, and eliminating several movable elements, viz., the presser bar and its associated actuating mechanism. Such a simplification is of particular value in machines intended to operate at relatively high speeds, since every movable part of a knitting machine entails problems of accurate mounting and assembly, wear and tear, lubrication, weight, vibration, and the like, and these problems become of special and unusual magnitude where high-speed movements, especially oscillatory movements such as those of a presser bar, are involved.

I achieve the principal object of my invention by means of a design and association of parts whereby an electro-magnetic means may be successfully resorted to to perform the functions heretofore served by a presser bar or other mechanical device of the character described. Not only does such an improvement involve substantially no movable parts, but it lends itself readily to the higher speed machines and operations which are currently coming into greater use.

2

Briefly stated, the preferred practice of my invention involves the provision of a needle in which a turned-back beard of magnetically-responsive character is mounted on a needle shank which is substantially immune to magnetic forces, and the mounting of at least one electro-magnet in a position in which the beard is subjected to its magnetic force. By energizing and de-energizing the magnet in predetermined timed relation to the knitting operation, movements of the needle beard can be correspondingly effected.

So far as the broader phases of the present invention are concerned, it makes no difference whether the needle as a whole is reciprocated (as in warp knitting machines, for example, among others), or whether it remains stationary during the knitting operation (as in circular knitting machines, for example). But whatever the nature or mode of operation of the knitting machine may be, it will embody, of course, a mechanism adapted to perform a knitting operation upon yarn supplied to it, a main drive shaft actuating this mechanism, and a magnetically-controlled needle beard of the character referred to, the electro-magnetic means being operated in timed relation to the knitting operation, and preferably by a means actuated by the main drive shaft of the machine. For example, I contemplate that the electro-magnet or magnets will be controlled by an electric circuit, and that a suitable switch means may be actuated by the main drive shaft (or subordinate mechanism driven by the shaft) to make and break the electric circuit in the desired timed relation to the knitting operation.

Of course, there will be as many electro-magnets as may be needed to control the needles involved. Thus, in a warp knitting machine, for example, or in any machine where a large multiplicity of needles are simultaneously operated during the knitting procedure, a plurality of electro-magnets will be arranged side by side along a suitable support extending lengthwise of the machine, i. e., parallel to the bank of needles. On the other hand, in a circular knitting machine or the like, where only one or at most a small group of needles is operative at any instant of time, one electro-magnet may be sufficient. It will be understood, also, that a single electro-magnet may be operatively associated with a group of adjacent needles, and that the invention does not necessarily contemplate that there shall be a separate electro-magnet in association with each needle.

In a relatively simple and preferred embodiment of my invention, the beard of the needle

is resiliently articulated to the shank, as in the ordinary "spring-beard" needle, and the beard normally assumes an open position spaced from the shank. The electro-magnetic means, in such a case, is positioned to exert its force upon the needle beard at predetermined time intervals to move it into a closed position against the shank, the resilient articulation being relied upon to return the beard to its open position after the magnetic force has ceased to act. Or, conversely, a needle may be employed in which the inherent resilience presses the beard normally against the shank, and in such a case the electro-magnetic means may be positioned and arranged to exert its force so as to open the crook of the needle at predetermined times. An unusually efficient result can be achieved by a third alternative design in which the beard is resiliently urged into a normal position intermediate between the fully-open and the fully-closed positions, and in which a pair of electro-magnets are arranged to exert their forces from opposite sides of the needle at predetermined successive time intervals, one magnet serving to move the beard into its fully closed position, the other magnet serving to move it into its fully open position.

I achieve the foregoing general objects and advantages, and such other objects and advantages as may hereinafter appear or be pointed out, in the manner illustratively exemplified in the accompanying drawings in which:

Figures 1-5 are diagrammatic views showing successive stages in a typical knitting operation, and showing an illustrative installation of an improved mechanism of the present character;

Figure 6 is a fragmentary perspective view of a portion of the knitting instrumentalities in the relationship they assume in an actual machine, an illustrative electric circuit being shown diagrammatically;

Figure 7 is an enlarged longitudinal cross-section through a knitting needle of the present character;

Figures 8 and 9 are views similar to Figures 1-5, illustrating a modification of the invention; and

Figure 10 is a similar view illustrating a further modification.

Merely by way of example, I have chosen to illustrate the present invention as it may be applied to a so-called warp knitting machine. Some of the parts of such a machine are shown in operative relationship in Figure 6. In this figure I have shown a multiplicity of knitting needles 20 extending upwardly from a needle bar 21. During the operation of the machine, which is well-known per se, the needle bar 21 is caused to reciprocate in an up-and-down direction by an actuating mechanism driven from a main drive shaft. The shaft 22 may be considered to be a drive shaft of this character, or a subordinate shaft driven thereby.

At 23 I have indicated a sinker bar which carries, in well-known fashion, a series of flat sinker elements 24 arranged in parallel spaced relationship and extending through the spaces between the needles 20. During the operation of the knitting machine, the sinker bar 23 is caused to reciprocate in a forward-and-back direction, in timed relation to the needle reciprocation. The bar 23 is suitably actuated in the desired timed relationship by the main drive shaft, such as the shaft 22.

I have also shown an illustrative guide bar 25 which carries a plurality of depending apertured elements 26. In a warp knitting machine, these

are the elements which feed the yarn to the needles. During the operation of the machine, the guide bar 25 has a primary reciprocating movement in a generally forward-and-back direction, each of the elements 26 passing through one of the spaces between the needles 20. The guide bar 25 also reciprocates, in accordance with a predetermined plan, in a longitudinal direction so as to effect the desired formation of yarn loops around predetermined needles. The guide bar 25 is actuated by mechanism which is driven by the main drive shaft.

None of the actuating mechanism has been illustrated in the present drawings since it is generally well-known per se, and since it has no direct bearing upon the present improvement. However, it will be understood that the various parts are driven in such predetermined timed relationship that a series of knitting operations are successively performed. An illustrative cycle is best shown in Figures 1-5. In each of these figures, I have shown one of the needles 20 and one of the guide bar elements 26; and I have indicated in dot-and-dash lines the general disposition of the sinker elements 24. In Figure 1, the needle 20 has its turned-back beard 27 in an open yarn-receiving disposition with respect to the shank of the needle, and the guide bar element 26 has just completed a movement which has engaged the yarn strand 28 within the crook of the needle. The needle is in a raised position. The needle now starts to descend for the purpose of pulling the strand 28 through the previously-knitted loop 29. During this descending movement, as indicated in Figure 2, the needle beard 27 moves into its closed disposition with respect to the needle shank, thus entrapping the yarn 28 within the crook of the needle, and permitting the needle to pass completely through the loop 29. During this procedure, the sinker 24 moves toward the left, as a comparison of Figures 1 and 2 will indicate.

After the free end of the beard 27 has safely passed through the loop 29, it is no longer necessary that it remain in its closed position, and the continuing descent of the needle is indicated in Figures 3 and 4, showing how the yarn 28 is pulled through the loop 29 in order to form a new loop 30.

In Figure 4 the needle is in its lowest position, and in Figure 5 the needle has risen to its highest position. In the meantime, the sinker 24 has moved into the position shown in Figure 5, to hold the newly-formed loop 30 down while the needle 20 moves upwardly. It will also be observed that the guide bar element 26 has swung into a position in readiness for forming a new loop of the yarn 28 in the crook of the raised needle.

My present invention is directed primarily to the opening and closing movements of the needle beard 27. In the embodiment illustrated in Figures 1-5, this is accomplished by mounting an electro-magnetic means 31 in a position which subjects the needle beard 27 to the electro-magnetic force at the time that the needle beard 27 is to be moved into its closed position. The needle illustrated is of the usual character in which there is a resilient articulation between the needle beard 27 and the needle shank. This articulation is in the turned-back region 32, which is resiliently constructed so that the needle beard normally assumes the position shown in Figures 1, 3, 4 and 5, but may be urged into the position

of Figure 2; against the action of its inherent resilience.

In Figure 1, the electro-magnetic means 31 is inoperative. In Figure 2, the dotted lines 33 are intended to indicate that the electro-magnetic means is operative and is producing an electro-magnetic field which exerts its force upon the needle beard 21. The magnet 31 is not shown in Figures 3-5, and is inoperative during the phases of operation shown in these figures.

A practical embodiment of the invention is most clearly shown in Figure 6 in which I have illustratively shown the electromagnetic means in the form of a series of adjacent U-shaped magnets. For the sake of convenience, I have designated these magnets by the reference numeral 31. They are mounted side-by-side upon a supporting bar 34 which extends lengthwise of the machine. It will thus be observed that each magnet controls the operation of a series of adjacent needles 20, the bank of magnets conjointly producing, at desired predetermined times, a magnetic field which affects an entire series of needles.

The magnets need not necessarily be U-shaped, as will be understood, and any magnet construction or design may be employed, provided it produces the desired electro-magnetic field in the desired region of the machine. For illustrative purposes, I have diagrammatically shown the type of electric circuit which may be employed for controlling the magnets. A suitable energizing coil is formed around each magnet. One end of the coil is connected as at 35 to the conductive portion 36 of a control wheel or switch 37. The other end of the coil is connected, as at 38, to one terminal 39 of a suitable source of electric power. A rheostat 40 is preferably arranged with-in the lead wire 38, for such adjustments in magnetic strength as may be desired from time to time.

The make-and-break or switch device 37 has been illustratively shown in the form of a wheel or disk mounted on the shaft 22. The conductive portion 36 is arranged on the periphery of this wheel, and is adapted to ride over an electric contact 41 which leads from the other terminal 42 of the source of electric power. The balance of the peripheral surface of the wheel 37 is suitably insulated. As a result, when the shaft 32 rotates, the electric circuit is periodically established and broken, in predetermined timed relation to the knitting operation, as the contact element 41 makes and breaks electric contact with the conductive portion 36.

The various coils on some or all of the magnets 31 may be interconnected in parallel as indicated by the connecting wires 43 and 44. For producing certain effects, a predetermined group of magnets may for example be energized and de-energized independently of another group or groups of magnets; although all magnet-actuation is always effected in a predetermined timed relation to the knitting operation itself.

Attention is now directed to Figure 7 in which I have shown one of the needles on a greatly enlarged scale. In this view I have more clearly shown the shank 45, the resilient articulation 46, and the needle beard 47, and I have shown the preferred arrangement of a slight recess 48 in the shank, within which the free end of the beard 47 disposes itself when the beard is adjusted into its closed position.

The line of demarcation 49 is intended to indicate, diagrammatically, that the material of the

beard 47 is different, from a magnetically-responsive standpoint, from the material of the shank of the needle. This difference resides in the fact that the needle beard 47 is purposely constructed in such a way that it is readily responsive to electro-magnetic force, while the material of the needle shank is purposely made of a material which is relatively immune to such force. This may be achieved in various ways. For example, 10 the shank may be composed of stainless steel or equivalent alloy which is relatively immune to magnetism, while the beard 47 may be composed of carbon steel or equivalent material which is relatively responsive to magnetism. Where different materials are employed, the parts may be separately manufactured, and then welded together at the line or in the region 49, any convenient welding procedure being utilized for this purpose. In the alternative, the shank and needle 20 beard may be formed of a single element, and the beard 47 subsequently treated (for example, by chemical action or electroplating or the like), to impart a relatively magnetically-responsive quality to the beard.

25 In Figures 8 and 9 I have illustrated an obvious alternative arrangement in which the electro-magnetic means 50 is arranged on the opposite side of the needle 51. In this case, the resilient articulation in the region 52 is of such a character that the beard 53 normally assumes the closed position shown in Figure 9, whereby the action of the electro-magnet 50 (indicated by the lines of magnetic force 54) serves to draw the beard 53 away from the shank and thus open the needle 35 so that it may receive the yarn 55.

An unusually efficient arrangement, constituting a third alternative, is shown in Figure 10 in which the needle 56 has a beard 57 resiliently articulated thereto at 58 in such a manner that 40 the beard normally assumes an intermediate position indicated in full lines. In this position, the beard is neither in its fully-closed nor in its fully-open position, and a pair of electro-magnets 59 and 60 are arranged on opposite sides of the needle. The magnet 59 serves at predetermined time intervals to draw the beard 57 into the closed position represented by the dotted lines 61; while the magnet 60 functions at other predetermined time intervals to draw the beard 57 into its fully-open position represented by the dotted lines 62. This arrangement is desirable, despite the provision of a pair of magnets, because less electric power is needed to effect the desired movements of the needle beard. The magnets 59 and 60 are 50 energized and deenergized at predetermined times by a pair of switch arrangements such as that shown in Figure 6, one switch arrangement controlling one of the magnets, the second switch arrangement controlling the other magnet, but both of them being operated in predetermined timed relation to the main drive shaft of the machine.

55 It will readily be understood that my invention is by no means restricted to a warp knitting machine of the character shown, nor to the various details herein illustrated by way of example. Thus, any type of make-and-break mechanism may be employed, other than that diagrammatically represented by the wheel 37 of Figure 6. 60 For example, a photo-electric device may serve to make and break the circuit at the desired time intervals, or a relay may be interposed between the source of power and the actual make-and-break mechanism.

70 In general, it will be understood that the de-

tails herein described and illustrated may obviously be modified by those skilled in the art in a number of respects, without departing from the spirit and scope of the invention as expressed in the appended claims.

Having thus described my invention and illustrated its use, what I claim as new and desire to secure by Letters Patent is:

1. In a knitting machine, a needle comprising a shank and a turned-back beard, said beard being adapted to move toward and away from said shank during the knitting operation, said beard being composed of a material readily responsive to magnetic force, an electro-magnet positioned to exert its force upon said beard and thereby

15 effect movements of the latter, and means for energizing and de-energizing said electro-magnet in timed relation to the knitting cycle.

2. In a knitting machine, a needle comprising a shank and a turned-back beard, said beard being adapted to move toward and away from said shank during the knitting operation, said shank being composed of a material which is substantially non-responsive to magnetic force, said beard being composed of a material which is readily responsive to such force, and an electro-magnet positioned to exert its force upon said beard and thereby effect movements of the latter.

RUDOLPH BASSIST.
